UNITED STATES PATENT OFFICE.

WILLARD T. GRUBB, OF SPRINGFIELD, ILLINOIS.

GOLF BAG.

Application filed December 21, 1925. Serial No. 76,893.

This invention relates to golf bags and has for its object the provision of a novel bag for carrying golf clubs, balls and other accessories used in the game.

5 An important object of the invention is to provide a bag provided with means whereby the iron clubs will be prevented from contacting with the shafts or handles of the wooden clubs, thereby avoiding damage to the latter as is bound to occur when clubs of these different types are jumbled together in an ordinary type of bag.

More specifically, the object of the invention is to provide a golf bag provided at 15 the center of its open end with a ball carrying pocket which will act to define spaced compartments within one of which may be carried the iron clubs while the wooden clubs are carried in the other, the pocket serving 20 to keep the two types separated so that the heads of the former cannot chafe, mar or otherwise damage the shafts or handles of the latter.

A further object is to provide a bag of 25 the character mentioned which is of oval or elliptical shape in cross section so as to provide ample storage capacity at the opposite sides of the centrally arranged ball pocket.

Yet another object of the invention is to 30 provide a bag of this nature having a peculiar and novel pocket structure of such form that it will retain its shape but which will nevertheless be capable of yielding in case the handles or shanks of the clubs press 35 thereagainst, the pocket structure further including supporting elements secured to and forming part of the frame structure at the open end of the bag, these bag forming or supporting elements constituting a very efficient reinforcement for the open end of the 40 bag for bracing and stiffening it and preventing it from becoming distorted after prolonged use of the bag or in case the bag is carelessly handled and thrown down or 45 dropped.

An additional object is the provision of a bag of this character which will be simple and inexpensive in manufacture, neat and attractive in appearance, convenient to use, 50 efficient and durable in service, and a general improvement in the art.

With the above and other objects and advantages in view, the invention consists in the details of construction and arrangement 55 of parts to be hereinafter more fully de-

scribed and claimed, and illustrated in the accompanying drawing in which:

Figure 1 is a perspective view of a golf bag constructed in accordance with my invention,

60 Figure 2 is a plan view looking at the top or open end,

Figure 3 is a central longitudinal section taken on the line 3—3 of Figure 2 with the carrying strap omitted and the closure flap 65 for the pocket open, and

Figure 4 is a detail perspective view of the frame for the open end of the bag.

Referring more particularly to the drawings, the numeral 10 designates the bag as 70 a whole which may be constructed of any preferred material and which may of course vary in size. This bag includes the usual elongated body which is, however, preferably elliptical in cross section for a reason 75 to be explained. One end is closed and the other open, as is customary, and the usual handle 11 and carrying straps 12 are provided.

In the present instance the bag is shown 80 as including a bottom member 13 and a top frame 14, both of which are connected by stays or braces 15 which extend longitudinally of the bag and which are riveted or otherwise suitably secured to the top and 85 bottom members. These stays are in the present instance represented as located at the ends of the minor axes of the elliptical top and bottom members and enclosed within pockets 16 formed in or secured upon the material from which the bag itself is 90 formed.

An important feature is the specific construction of the top frame member 14, which, 95 actually, includes a band or hoop 17 bent into the required shape with its ends preferably overlapped and riveted or otherwise secured as shown at 18. The frame or band is enclosed within a binding 19, preferably of leather, which will act to prevent contact 100 between the handles or shanks of the clubs and the metal frame.

Located centrally of the open top of the bag is a pocket structure 20 within which may be carried balls and various accessories such as score cards, tees or the like. The construction of this pocket is an important matter and it is here shown as including a pair of spaced parallel angular brackets 21 which 110 extend transversely of the hoop or band

17 at opposite sides of the minor axis thereof, the end portions 22 of these brackets extending preferably toward each other and being riveted or otherwise suitably secured to the band or hoop so as to serve not only as a support for the pocket structure but also as reinforcements or bracing elements which will act to stiffen and rigidify the open end of the bag so as to prevent col-
 10 lapsing or distortion thereof in case of rough handling or as the result of prolonged use. Secured to the brackets 21, as for instance by rivets 21^a or the like, and depending therefrom are flexible sheet mem-
 15 bers 23 covered at least externally with fabric indicated at 24 which also passes about the brackets 21 to form a sheathing therefor and to prevent injury to the hand of the user when rummaging about in the
 20 pocket during the act of placing articles therein or removing them therefrom. The sheet members 23 are spaced apart and are entirely separate throughout, that portion 25 of the fabric which extends between the
 25 sheet members constituting the bottom of the pocket. The sheet members 23 or the fabric covering 24, or both, may be secured to the opposite sides of the bag as by stitching indicated at 26 though it is conceivable
 30 that some other means might be provided.

With the pocket arranged in this manner it is clear that there are two compartments 27 and 28 defined at opposite sides thereof, within which compartments may be placed
 35 the clubs needed by the user. It is intended that the iron clubs A be carried in one compartment and that the wooden clubs B be carried in the other. The pocket 20 is of such size that it will maintain the iron clubs
 40 in such position that the heads thereof cannot come in contact with the shafts or handles of the wooden clubs. Obviously this feature is of importance inasmuch as there will be no chafing of and consequent
 45 damage to the handles of the wooden clubs. Owing to the elliptical shape of the bag, in cross section, it will be apparent that there will be ample space provided at opposite sides of the pocket for the accommodation
 50 of quite a number of clubs.

The pocket is intended to carry balls and other objects, and to prevent loss thereof, one flexible sheet member 23 is prolonged or formed with an extension constituting a cover or flap 29, this flap being equipped with a buckle or equivalent device 30 with which coats a strap 31 secured to the opposite side of the pocket.

The device is used in exactly the same manner as any other golf bag except that the two different types of clubs are intended to be carried in the separate compartments for reasons above mentioned. The location of the pocket within the open end of the bag is a great convenience inasmuch as it

obviates the necessity of providing a pocket on the side of the bag as is the common practice. The device is bound to be of great benefit inasmuch as the clubs will be kept in better conduit and saved from being 70 chafed, scratched or otherwise damaged, a factor worth considering when the high cost of certain of clubs is taken into account.

While I have shown and described the 75 preferred embodiment of the invention, it should be understood that I reserve the right to make such changes in the form, construction and arrangement of parts as will not depart from the spirit of the invention or 80 the scope of the subjoined claims.

Having thus described the invention, I claim:

1. A golf bag provided with a ball carrying pocket extending transversely thereof 85 within its open end, the pocket defining spaced compartments for the storage of clubs and terminating a short distance inwardly from the open end.

2. In a golf bag having a closed bottom 90 and an open top, a frame located within the open top, a pair of spaced metallic bracket members secured within said frame, and a pocket carried by said brackets and located within the open end of the bag, the pocket 95 terminating a short distance inwardly of the open end.

3. In a golf bag having a closed bottom and an open top, a frame located within the open top, a pair of spaced metal bracket 100 members secured rigidly and permanently to and located within said frame, and a pocket carried by said brackets and located within the open end of the bag, said pocket including flexible side sheets and a fabric covering 105 therefor.

4. In a golf bag having a closed bottom and an open top, a frame located within the open top, a pair of spaced bracket members secured within said frame, and a pocket carried by said brackets and located within the open end of the bag, said pocket including flexible side sheets and a fabric covering 110 therefor, said sheets being arranged in spaced parallel relation, and the fabric 115 covering extending across the space between the inner or lower ends of the sheets to define a bottom for the pocket.

5. In a golf bag having a closed bottom and an open top, a frame located within the open top, a pair of spaced bracket members secured within said frame, a pocket carried by said brackets and located within the open end of the bag, said pocket including flexible side sheets and a fabric covering 120 therefor, one sheet being prolonged to define a cover for the pocket, and means for securing the cover in closed position.

6. In a golf bag, a bottom member, a metallic elliptical top frame member, longi- 125

tudinally extending stays connecting the top and bottom members, a flexible bag structure secured to the top and bottom members, spaced angular metallic brackets having 5 their end portions secured to the top member at opposite sides of the points of connection of the stays therewith, and a pocket carried by said bracket members and extending across and a short distance into the 10 open end of the bag, the spaces between the opposite sides of the pocket and the adjacent portions of the bag constituting separate storage compartments within which clubs of different types may be carried, the pocket having a width sufficient to prevent contact 15 of the heads of clubs within one compartment with the shafts or handles of clubs carried within the other compartment.

In testimony whereof I affix my signature.

WILLARD T. GRUBB.
